INVENTOR:

Jacob Falbel

UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 837,920.

Specification of Letters Patent.

Patented Dec. 11, 1906.

Application filed January 3, 1903. Serial No. 137,682.

To all whom it may concern.

Be it known that I, JACOB FELBEL, a citizen of the United States, and a resident of the borough of Manhattan, city of New York, in the county of New York and State of New York, have invented certain new and useful Improvements in Type-Writing Machines, of which the following is a specification.

My invention relates to type-writing machines, and more particularly to type-bar baskets or rests therefor.

The object of my invention is to provide a simple construction of type-bar basket or rest which is capable of greatly reducing the rebound of the type-bars when they strike the basket in their movements back to normal positions, and thereby avoid the liability of adjacent type-bars conflicting or colliding near the type-bar basket during the rapid operation of the machine.

To the above and other ends which will hereinafter appear my invention consists in the features of construction and combinations and arrangements of devices hereinafter described, and more particularly pointed out in the appended claims.

In the accompanying drawings, wherein like reference characters indicate corresponding parts in the various views, Figure 1 is a central front to rear sectional view of one form of type-writing machine embodying my invention. Fig. 2 is a detail longitudinal sectional view of one form of the basket embodying my invention, the view being taken on the line *x-x* of Fig. 1 and looking in the direction of the arrow in said figure. Fig. 3 is an enlarged detail fragmentary perspective view of the pad shown in Figs. 1 and 2. Fig.

4 is a detail front elevation of a composite pad and made up of segmental sections.

Fig. 5 is an enlarged detail fragmentary perspective view showing one end of a composite pad and one means which may be employed for uniting the strips of which said pad is composed. Fig. 6 is an enlarged detail fragmentary perspective view of another form of pad, the view illustrating still another manner of securing the strips together. Figs. 7, 8, and 9 are like views of other forms of pads embodying my invention.

While I have shown my invention as employed in a front-strike type-writing machine, it should be understood that it may be

used in any style of type-bar writing-machines.

The frame 1 of the machine is surmounted by a top plate 2, which supports a suitable carriage (not shown) provided with a platen 3. (Diagrammatically illustrated in Fig. 1.) Key-levers 4 are pivoted in the frame of the machine at 5 and have the usual finger-keys 6 at their forward ends. Each key-lever has a restoring-spring 7 and has a sublever 8 pivoted thereto at 9, the lower portion of the sublever being slotted at 10 for coöperation with a fixed fulcrum-rod 11, that extends from side to side of the machine. To the upper end of each sublever is pivoted at 12 a link 13, that in turn is pivoted at 14 to a type-bar 15. The various segmentally-arranged type-bars are mounted upon a pivot-wire 16, seated in a segment 17, and are each restored to normal position by a returning-spring 18, connected at one end to a link 19, pivotally connected at 20 to a type-bar, and connected at its other end to a hook 21, secured to the segmental type-bar basket, which is designated as a whole by the numeral 22. The type-bars, which are adapted to strike upwardly and rearwardly, normally rest at their forward free ends on a segmental pad 23, which is supported in a rigid, preferably metal, segmental support 24, that is trough-like or U-shaped in cross-section to receive the pad and form a support therefor. Said support is back of or in rear of the pad and extends throughout or substantially throughout the length of the latter. The support 24 is secured to or held by arms 25, that extend forwardly from the type-bar segment 17.

The pad 23 may be made up of a plurality of strips, as 26 and 27, that extend longitudinally of the pad, and are secured together by any suitable means, or the pad may be made of a single body of felt or other suitable material, as at 26^a. The composite pad may be constructed as illustrated in Figs. 1, 2, 3, 4, 5, and 9, with an uppermost or outermost longitudinally-extending strip 26 of soft or resilient material, such as felt or the like, and with a lowermost or rearmost longitudinally-extending strip 27 of leather or other suitable material having less resiliency than felt, or the pad may be made of a single strip of soft, yielding, or resilient material, such as felt, as

indicated at 26^a in Figs. 7 and 8, or of two or more strips of felt or soft material secured together, as illustrated at 26^b and 26^c in Fig. 6. The pad in each case, however, has embedded or seated therein a longitudinally-extending strip or strips of metal, preferably of a non-resilient character, such as copper or lead, and this metallic strip is wholly supported by the pad itself. Preferably the felt or yielding surface of the pad is exposed for the impact of the type-bars in order to deaden the sound as much as possible. In Figs. 1, 2, 3, 5, 6, and 7 the inserted strips of metal are indicated as wires 28, which extend longitudinally of the pad and from end to end thereof. The pads shown in Figs. 1, 2, 3, and 5 are preferably formed by scoring or kerfing the leather strip to a depth that corresponds substantially to one-half the diameter of a wire, and a wire may then be seated in each longitudinally-extending groove or kerf if two or more wires be employed. The felt strip is then placed in position and compressed on the leather strip so that the wires will sink into the felt, and the two strips and the wires are then secured together in any suitable manner. The strips may be cemented or glued together, or they may be sewed together by lines of stitches 29, as indicated in Fig. 6, or they may be secured together at their ends by rivets 30, the upper or outer heads of which may be countersunk in the felt strip 26 in order that the type-bars shall not come into contact with the rivets.

I prefer to make the pads of straight pieces of the requisite lengths and bend them as a whole over a suitable mandrel, or the pad may be given the requisite curvature by the same machine which is employed to bend the rigid support 24.

Where a single body of felt or like material is employed, as in the construction shown in Figs. 7 and 8, the metallic antirebounding strip or strips may be driven into the felt endwise, or the felt may be split or cut to receive the strip or strips.

Instead of employing one or more strips in wire form, as thus far specifically described, one or more strips of metal 28^a, of sheet-like or other form, may be seated in the pad, as represented in Fig. 8, or a single strip of sheet metal 28^b may be interposed between two inclosing strips, as represented in Fig. 9. In this case the uppermost strip 26^d is preferably made of felt, and the lowermost strip 27^a is preferably made of leather, though it should be understood that both upper and lowermost embracing strips may be made of felt or some other suitable soft or yielding material, as indicated in Fig. 6, and that these strips with the interposed sheet-metal antirebounding strip 28^b may then be secured together in any suitable manner. The antirebounding strips of metal 28^a and 28^b are

preferably made of copper, lead, or some such non-resilient metal.

Instead of making the pad of a single continuous strip, or of continuous strips, as shown in Fig. 2, they may be divided into a plurality of segmental sections *a*, *b*, and *c*, as represented in Fig. 4, and seated within the U-shaped rigid support. Either the pads, together with the metal strip or strips seated therein, may be thus divided, or the metal strip or strips may be continuous and the pad itself made in sections.

From the foregoing description it will be understood that the non-resilient or hard antirebounding strips are seated and fixed within the pads and are wholly supported thereby, that the metal strip or strips are independent of the support for the pad, that certain of the pads shown are divided longitudinally and that the metal strips in such pads are interposed between the plies thereof or are seated within the divided portions, that the metal strips are surrounded on all sides by the pad, that grooves are formed in the meeting faces of the inclosing pads, and that the metal strips are seated in said grooves, that in some cases the grooves are formed by scoring or grooving the non-metallic strip and in others by pressing the non-metallic strips upon the metal strips or wires.

It will be observed that all of the inserted antirebounding strips are harder and stiffer than the surface of the pad against which the type-bars strike, and said strips being unsuspended they operate greatly to reduce the rebound of the type-bars.

I have used in practice the forms shown in Figs. 1, 3, 5, and 7 with highly satisfactory results, since the pad is practically noiseless and the rebound so largely reduced as to avoid all clashing of the type-bars.

While I have illustrated several forms of my invention, it should be understood that various changes in construction may be made without departing from the spirit thereof.

Although I prefer and have successfully used in practice a metal strip, as 28, nevertheless in so far as my invention broadly is considered some other equivalent material may be employed instead, the gist of the improvement consisting in providing the pad with an inserted rebound-reducing strip, as will be more exactly defined in the following claims.

What I claim as new, and desire to secure by Letters Patent, is—

1. In a type-writing machine, the combination of a pad, a support arranged back of said pad and wholly supporting the pad, and a non-resilient longitudinally-arranged antirebounding strip supported wholly by said pad.

2. A type-bar basket comprising a seg-

5 mental pad, a segmental support back of and against which the pad bears throughout its length and by which the pad is wholly supported, and a segmental antirebounding strip that is embedded in said pad and extends longitudinally thereof.

10 3. A type-bar basket comprising a felt pad, a rigid support that is back of and wholly supports said pad substantially throughout the length thereof, and an antirebounding wire that extends longitudinally of and is wholly supported by the pad and is surrounded on all sides thereby.

15 4. A type-bar basket comprising a pad, a support back of and against which the pad bears throughout its length, and a non-resilient antirebounding strip that extends longitudinally of the pad and is embedded and fixed therein and is independent of said support.

20 5. A type-bar basket comprising a pad having a felt impact-face, a support for wholly supporting said pad, and a series of non-resilient metallic antirebounding strips that are arranged side by side and extend longitudinally of and are embedded and fixed in the pad and are supported thereby.

25 6. In a type-writing machine, the combination of type-bars, a composite pad, a support back of the pad and against which the pad bears and by which the pad is wholly supported, and a metallic antirebounding strip seated in said composite pad and extending longitudinally thereof and wholly supported thereby.

30 35 7. In a type-writing machine, the combination of type-bars, a segmental support, a segmental pad that is wholly supported throughout its length by said support, and a segmental non-resilient antirebounding strip that is fixed and seated in said pad and supported thereby.

40 45 8. A type-bar basket comprising a pad that is divided longitudinally, a support arranged back of said pad and wholly supporting it, and a metallic antirebounding strip that extends longitudinally of the pad and is seated and supported therein at its divided portion.

9. A type-bar basket comprising a pad made up of a plurality of sections, a metallic antirebounding strip that is interposed between said sections and extends longitudinally thereof, and a support back of said pad

and against which the pad bears and by means of which the pad is wholly supported.

10. A type-bar basket comprising a pad made up of a plurality of strips which have grooves in their meeting faces, a metallic antirebounding strip seated within said grooves and an independent support back of said pad and against which the pad bears and by which it is wholly supported.

11. A type-bar basket comprising a pad made up of a plurality of strips having grooves in their meeting faces, which grooves extend longitudinally of the strips, a longitudinally-extending metallic antirebounding strip seated in said grooves, and an independent support back of said pad and against which the pad bears and by which it is wholly supported.

12. A type-bar basket comprising a pad made of a plurality of strips having longitudinally-extending grooves in their meeting faces, the strip which receives the impact of the type-bars being made of felt, longitudinally-extending rebound-reducing strips seated in said grooves and wholly supported thereby, and a support back of said pad and against which the pad bears and by which it is wholly supported.

13. A type-bar basket comprising a pad made up of a plurality of sections, a longitudinally-extending metallic antirebounding strip contained between the meeting faces of the sections and supported thereby, means for securing said sections together, and a support back of the pad and against which the pad bears and by which it is wholly supported.

14. A type-bar basket comprising a pad made up of a plurality of strips secured together, the strip exposed to the impact of the type-bars being made of felt, a rebound-reducing strip seated between said other strips and extending longitudinally thereof, and means wholly independent of said rebound-reducing strip for supporting said pad.

Signed at the borough of Manhattan, city of New York, in the county of New York and State of New York, this 2d day of January, A. D. 1903.

JACOB FELBEL.
